HOSIERY

Leander Lockes, 3815 Norfolk Ave.,
Baltimore, Md. 21216

Filed Mar. 28, 1973, Ser. No. 345,682

Term of patent 7 years

Int. Cl. D2—04

U.S. Cl. D2—342

FIG. 1

FIG. 2

FIG. 1 is a side perspective view of a stocking showing my new design, the other side being substantially similar thereto; and

FIG. 2 is an enlarged fragmentary view of the mid-portion of the stocking.

I claim:

The ornamental design for hosiery, as shown and described.
